Primary Examiner — Rhea Shields

(57) **CLAIM**

The ornamental design for an electric apparatus for the hair, as shown and described.

DESCRIPTION

Figure 1.1 is a front perspective view;

Figure 1.2 is a rear view;

Figure 1.3 is a bottom view;

Figure 1.4 is a front view;

Figure 1.5 is a top view;

Figure 1.6 is a side view; and

Figure 1.7 is a rear perspective view.

The internal features shown in 1.2 form no part of the claimed design.
